EXERCISER

Frank E. Wolcott, West Hartford, Conn.

Application July 3, 1929, Serial No. 375,634

4 Claims. (Cl. 128—63)

My invention relates to exercisers.

It has for its object to provide an improved exerciser. Other objects of my invention are to provide an improved exerciser unit and improved supporting means cooperating therewith whereby all necessity for providing a separate exerciser stand or table, constituting an additional piece of furniture, is eliminated. A further object is to provide an improved exerciser 5 having supporting means adapted to be conveniently supported in any usual doorway, such, for example, as a closet doorway, and also adapted when not in use to be conveniently and compactly disposed out of the way inside the door, as for example, inside the closet. A still further 10 object of my invention is to provide an improved exerciser adapted to be manufactured at small expense. These and other objects and advantages of my improved construction will, however, 15 hereinafter more fully appear.

In the accompanying drawings, I have shown for purposes of illustration one embodiment which my invention may assume in practice.

In these drawings,—

25 Figure 1 is a perspective view of my improved exerciser in use when positioned in a doorway;

Fig. 2 is a front view of the device when in use in a doorway;

Fig. 3 is a sectional view on line 3—3 of 30 Fig. 2;

Fig. 4 is a plan view of the device shown in inoperative position;

Fig. 5 is a side view of the exerciser in Fig. 1 when the same is not in use;

35 Fig. 6 is a partial sectional view of one end of the exerciser unit;

Fig. 7 is a similar view of a modified construction wherein the whole end of the motor is enclosed, and

40 Fig. 8 is a perspective view of a modified construction wherein posts other than those in a door-frame are used.

In this illustrative construction I have shown an exerciser unit, generally indicated at 1, of 45 the motor type, and including at each end of its motor shaft 2 improved exerciser operating elements 3, hereinafter described, carrying a usual belt 4; the unit 1 being also mounted on an improved support 5 supported adjustably in an improved manner relative to suitable improved supports 6 and 7 on a door frame 8.

50 Referring more particularly to the exerciser unit, it will be noted that the members 3, which are fixed to the ends of the motor shafts 2, are in the form of rotatable cups having rounded belt

deflecting flanges 9 of any suitable length extending close to the ends 10 of the motor and forming a shroud partially or wholly, as shown in Fig. 7, enclosing the shaft and the usual connections carried on the motor ends. It will also 60 be noted that these members 3 are provided with a series of threaded apertures 11, 12, and 13, disposed on a flat end surface thereof and parallel to the motor shaft 2 and spaced from the axis of the latter by different distances, the aperture 65 11 being closest to the shaft, the aperture 12 next closest to the same, and the aperture 13 most remote from the shaft. In these apertures is selectively disposed a readily removable screw 70 or crank pin 14 herein having a reduced portion threaded into the same and also preferably carrying on its belt receiving portion or shank and between the latter and its slotted head 15, a sleeve 16 tending to reduce the wear on the belt end. Thus, it will be evident that with each end 75 of the motor shaft equipped with one of these members 3, and with the screws 14 displaced at 180° from one another as illustrated, it is made possible to obtain the desired degree of belt movement and to vary the same as desired through 80 changing the pins 14 to different sets of apertures 11, 12, 13. Moreover, during the use of the device the portions 9 act not only to balance the motor effectively but also as deflectors for the belt, in such manner as to prevent the latter 85 from dangerous engagement with any part on the motor during operation, such, for example, as the end bolts on the ends of the motor. It will also be noted that they obviate all necessity for the provision of any supplementary shroud or 90 shield carried by the motor, and that these rotating members, which are ordinarily highly polished, produce a very attractive device.

In my improved construction, this exerciser unit is also mounted in an improved manner. 95 Herein, it is carried on a base 17 preferably cupped, as at 18, to receive the round bottom of the motor casing, and on its opposite side seated on the support 5. It will also be noted that a pair of bolts 19, disposed at 60° to one another, 100 is extended through countersunk apertures 20 in the support 5 and through the base 17 and into the motor casing, in such manner that these two bolts act to hold the parts together securely. Attention is, moreover, directed to the fact that 105 in order to provide for the adjustment of the unit laterally relative to the support 5, series of similar apertures 21, 22 are also provided in the support 5 at either side of the central series 20. The support 5 is herein disposed vertically during 110

use, i. e. on one edge with its oppositely disposed enlarged flat surfaces in upright planes, as shown in Fig. 1, while its supporting means 6 and 7 at its ends are so connected to the doorway 8 as 5 to support the member 5 against the opposite side of the doorway 8 from the motor unit 1 and strap 4. Thus, it will be evident that it is not only made possible to put the device into use without any necessity for providing any separate 10 stand or table, as heretofore provided, but that the arrangement is also such that full advantage is taken of the stable abutment provided by the doorway, the pull on the belt 4 acting to bring the support 5 firmly against the latter. I find 15 in practice that the best results are obtained when this member 5 is slightly resilient, and that a wooden member 5 has, in addition to this desired resiliency, the added advantages of lightness and cheapness. Cooperating with the support 5 and 20 disposed at each end of the face thereof adjacent the door frame, I also provide a plurality of rubber buttons or studs 23, which are of such height as to form the means engaging the door frame, and of such resiliency as with the support 5 to 25 provide a very effective, silent and slightly yielding support. Moreover, it will be noted that through the use of these rubber buttons marring of the door frame is minimized.

The supporting means 6 and 7 associated with 30 the support 5 are also of improved construction. Herein, the support 6 is in the form of a U member formed of a single metal strap. Its body is also herein, as preferably, centrally attached to the door frame by a suitably washered swiveling 35 member 24, herein a screw having its head movable at will into a recess 24' in the member 5. The arms of this support 6 are also slotted, as at 40 25, and extend laterally across the upper and lower edges of one end of the support 5. These slotted arms herein also receive in their slots 45 vertical pins 26 preferably suitably set in an end strap 27 carried on that end of the member 5. The support 7, on the other hand, comprises a strap of suitable material adapted to receive the 50 opposite end of the support 5 from above and support the latter as illustrated in Fig. 1. This support 7 is also adapted to be attached to the door frame 8 by any suitable means, such, for example, as screws 28 beneath the same. Thus, 55 it will be evident that when the device is in use and pressure is exerted against the belt 4 in a usual manner, the support 5 will be held in the desired position by the supporting means 6 and 7, while the pull on the belt will cause the support 5 to press the rubber buttons 23 against the opposite sides of the door frame.

When the device has been used, my improved construction also makes it possible for it to be compactly disposed out of the way in such manner as to allow full use of the door and of the 60 closet between exercising periods. Herein, it will be noted that due to the swivel 24, the aperture 24', and the slot and pin connection 25, it is made possible for the support 5 to be lifted up out of 65 the support 7 and then turned about the pins 26 as it turns about the swivel 24, in such manner as to bring it into the depending position illustrated in Fig. 5, wherein it is vertically disposed parallel to one side of the door frame with its 70 lower end against a rubber button 29 on the door frame and with the unit 1 projecting inward rather than outward, as when in use. Thus, it will be noted that whenever desired the device may be conveniently taken down and disposed 75 out of the way without removing its support 6,

and that it is also then ready to be again placed quickly in position whenever desired by simply lifting the lower end of the support 5 and swinging and turning the same until it drops into the support 7 in the position illustrated in Fig. 1.

80

As a result of my improved construction, it is possible for the pins 14 to be adjusted prior to use in the apertures 11, 12, 13, in such manner as to vary the amount of vibration to be obtained as desired. Further, by reason of the rotating 85 combined deflecting, balancing and shrouding members 3, all danger of the belt being caught on the motor frame is obviated, at the same time that the motor is properly balanced and all necessity for providing additional and expensive stationary shrouding is obviated. My improved construction also makes unnecessary all stands held 90 by the weight of the operator, or tables or frames requiring a rigid connection to the floor or wall, instead being usable in any doorway. It is also 95 possible to place the support 5 and its supporting means 6 and 7 in any desired elevation in a doorway when it is desired to use the belt on different parts of the body. Further, through the use of the supplementary holes 22 and the independently adjustable supporting means 6 and 7, it is possible to adapt the device to use in doorways of different width. In this connection, attention is also directed to the fact that the support 5 may, when desired, be turned end for end 100

in order to adapt it to different conditions, while by using a wooden support 5, in addition to the advantages of resiliency and light weight, it is also made possible under extreme conditions for the user to adjust the necessary buttons 23 and 110 shorten the member 5 as desired, without in any way interfering with the rest of the device. The unit 1 in such cases, and whenever desired for other reasons, may also be adjusted into the supplementary holes 21, 22, which also adapt it to occupy a substantially central position in doorways of different width or for convenient use where for some reason a central position is not desirable. It will further be noted that when it is in its inoperative position the device is disposed close 115 to the door frame in such a position as to make it especially adapted to mounting inside doors such as closet doors and without interference with the articles hung in the closet, the support 5 being close to the door frame and the unit 1 ordinarily being below the articles in the closet and disposed so close to the door frame as in no way to interfere with access to the articles hung above it. Attention is also directed to the fact that through my improved construction it is made possible 120 to produce an exerciser apparatus which, while adapted to perform all of the functions of a table or stand mounted exerciser, has also additional possible adjustments and advantages not found therein and which is further adapted 125 to be manufactured and sold at a substantially lower figure, in such manner as substantially to increase the possible field of use of such devices. It will, of course, be understood that other exerciser means than a belt may be substituted if desired. These and other advantages of my improved construction will, however, be clearly apparent to those skilled in the art.

In Fig. 8 I have illustrated a construction where in the members 8, instead of being part of a door frame, are in the form of separate upstanding posts 30, herein suitably braced and attached at their lower ends, as at 31, this construction not being preferred, for reasons above noted, but being usable under certain conditions where desired 130

140

145

150

without change in the rest of the mechanism. Obviously, such upstanding posts may be used with the rest of my mechanism wherever desired, and when used in a doorway, or a closet doorway, eliminate any need for an attachment to or marring of the door frame.

While I have in this application described two forms which my invention may assume in practice, it will be understood that the invention is not limited thereto but may be modified and embodied in other forms without departing from its spirit or the scope of the appended claims.

What I claim as new and desire to secure by Letters Patent is:

15 1. An exerciser unit comprising a motor and rotating motor shrouding members at the ends of said motor, said members carrying crank pins.

2. An exerciser unit comprising a motor and

rotating motor shrouding members at the ends of said motor, said members carrying crank pins, and said shrouding members having external deflecting surfaces.

3. An exerciser unit comprising a motor and rotating motor shrouding members at the ends of said motor, said members carrying crank pins, and said shrouding members each having a series of apertures for selectively receiving its pin.

4. An exerciser unit comprising a motor and motor shrouding members at the ends of said motor, said members carrying crank pins, and each shrouding member having a series of apertures for selectively receiving its pin and disposed parallel to the motor shaft at different distances
